CLAIM

The ornamental design for a light reflector, as shown and described.

DESCRIPTION

FIG. 1 is a perspective view of a first embodiment of a light reflector, as viewed from above, showing my new design; FIG. 2 is a perspective view of the light reflector shown in FIG. 1, as viewed from below; FIG. 3 is a left side view of the light reflector shown in FIG. 1; FIG. 4 is a right side view of the light reflector shown in FIG. 1; FIG. 5 is a front elevation view of the light reflector shown in FIG. 1;

FIG. 6 is a rear elevation view of the light reflector shown in FIG. 1;

FIG. 7 is a top plan view of the light reflector shown in FIG. 1;

FIG. 8 is a bottom plan view of the light reflector shown in FIG. 1;

FIG. 9 is a perspective view of a second embodiment of a light reflector, as viewed from above, showing my new design;

FIG. 10 is a perspective view of the light reflector shown in FIG. 9, as viewed from below;

FIG. 11 is a left side view of the light reflector shown in FIG. 9;

FIG. 12 is a right side view of the light reflector shown in FIG. 9;

FIG. 13 is a front elevation view of the light reflector shown in FIG. 9;

FIG. 14 is a rear elevation view of the light reflector shown in FIG. 9;

FIG. 15 is a top plan view of the light reflector shown in FIG. 9; and,

FIG. 16 is a bottom plan view of the light reflector shown in FIG. 9.

The stippling shown in the drawings illustrates contrasted surface appearance and the stippling itself forms no part of the claimed design.
